UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRICAL APPARATUS.

Application filed July 29, 1926, Serial No. 125,680. Renewed May 10, 1927.

My invention relates to electrical apparatus, and particularly to apparatus for supplying currents of different frequencies from two sources to a single load such as the rails 5 of a stretch of railway track.

One object of the invention is the provision, in apparatus of the type described, of means for preventing the flow of current from one source through the other source.

10 I will describe one form of apparatus embodying my invention, and will then point out the novel features thereof in claims.

15 The accompanying drawing is a diagrammatic view illustrating one form of apparatus embodying my invention.

Referring to the drawing, the reference characters 1 and 1^a designate the track rails of a stretch of railway track over which traffic normally moves in the direction indicated by the arrow. These track rails are divided by means of insulated joints 2, into a plurality of successive track sections A—B, B—C, etc. Each track section is provided with a track transformer designated by the 20 reference character T with an exponent corresponding to the location and having a secondary 5 connected across the rails adjacent the exit end of the corresponding section through the usual impedance 7. The 25 primary 6 of each transformer T is constantly supplied with alternating current from a suitable source such as an alternator K over line wires 3 and 3^a.

Each track section is further provided 30 with a track relay designated by the reference character R with a suitable exponent and connected across the rails adjacent the entrance end of the corresponding section. Each track relay R is responsive to the track 35 circuit current supplied to the rails of the associated section by transformer T at the exit end of such section. The track relays R may be utilized in any desired manner to control trackway governing apparatus not 40 shown in the drawing.

Means are also provided for at times supplying each section with alternating train 45 controlling current. For this purpose each section is provided with a train control transformer designated by the reference character L with an exponent corresponding to the location and having its secondary 8 connected across the rails adjacent the exit end of the

corresponding section through an impedance 10. The primary 9 of each transformer L⁵⁵ is connected with line wires 4 and 4^a over a front contact 15 of the track relay R for the section next in advance. The line wires 4 and 4^a are constantly supplied with alternating current of a frequency different from 60 that of the track circuit current from a suitable source such as an alternator G. It follows that each track section is supplied with track circuit current from a track transformer T at all times, and that the rails 65 of each section are further provided with alternating train controlling current from the associated transformer L when the track relay for the section next in advance is energized. The train controlling current 70 supplied to the rails by the transformers L may be used to control train carried governing means, not shown in the drawing, in any suitable manner.

With only the apparatus thus far described it might happen that when a train occupies section B—C, train controlling current from transformer L^c would flow through secondary 5 of transformer T^c, thereby creating in primary 6 of transformer 75 T^c an alternating current of train control frequency which might flow through the line wires 3 and 3^a to transformer T^b and thereby supply train controlling current to the rails of section A—B even though the primary circuit for transformer L^b would 80 be open at front contact 15 of relay R^b. Current thus improperly supplied to the rails of the section immediately in rear of an occupied section might interfere with the 85 proper operation of the train carried governing means and might create a dangerous condition.

In order to prevent this, I provide apparatus for preventing the flow of current from 90 one of the transformers for each section through the secondary of the other transformer connected with the same section. To accomplish this result I connect a rectifier 12 of any suitable form in series with secondary 5 of each transformer T, and a similar rectifier 14 in series with secondary 100 8 of each transformer L. Due to the rectifiers 12 and 14, track circuit current and train controlling current are supplied to each section only during alternate half 105

cycles. The rectifiers 12 and 14 are so disposed that current of the same polarity is supplied to the rails by both transformers T and L. In other words, the rectifiers are so arranged that corresponding half cycles of alternating track circuit current and alternating train controlling current are supplied to the rails of each section. I also provide a rectifier 11 connected across secondary 5 of each transformer T and the associated rectifier 12, and a similar rectifier 13 connected across secondary 8 of each transformer L and the associated rectifier 14, each rectifier 11 and 13 being so disposed as to oppose the flow of current from the associated transformer during the half cycle that current is supplied from such transformer to the rails of the associated section. It will be seen that with this arrangement, during each half cycle of train controlling current supplied to the rails by the transformer L, the current is of such polarity as to be opposed by the rectifier 12 associated with the adjacent track transformer T^B . Furthermore current from a track transformer T is prevented from flowing through an adjacent train control transformer L by the associated rectifier 14. One purpose of the rectifiers 11 and 13 is to provide short circuit paths for energy which might tend to feed over from one transformer to another. Thus current tending to feed over from transformer L^B traverses rectifier 14 in its high resistance direction, but this current will be shunted by rectifier 13, the current flowing through 13 in the low resistance direction. In similar manner this stray current will also flow through rectifier 11 associated with transformer T^B in the low resistance direction. Similarly stray current tending to flow over from transformer T^B to transformer L^B will be shunted by the rectifiers 11 and 13.

Another purpose of the rectifiers 11 and 13 is to prevent improper operation should the associated series rectifier become short-circuited. For example, if rectifier 14 associated with transformer L^B should become short-circuited, the rectifier would pass train controlling current of the polarity normally suppressed but rectifiers 13 and 11 would shunt this current away from secondary 5 of transformer T^B , thereby preventing the flow of such current to the line wires 3 and 3^a.

It follows that with the apparatus embodying my invention it is impossible for train controlling current to be supplied to the line wires which supply the track circuit current to transformers T, and it is therefore impossible for train controlling current to be supplied to the rails of a section except by train control transformer L associated with that section. Furthermore it is impossible for track circuit current to

be supplied to the line wires which supply the train control transformers.

For purposes of explanation I have here assumed that the two sources of alternating current supply energy to the rails of a stretch of railway track but my invention may be applied equally well to any two sources of alternating current which supply a single load.

Although I have herein shown and described only one form of apparatus embodying my invention, it is understood that various changes and modifications may be made therein within the scope of the appended claims without departing from the spirit so and scope of my invention.

Having thus described my invention, what I claim is:

1. In combination, a stretch of railway track, two sources of alternating current of different frequencies connected with the rails of said stretch, and two rectifiers one interposed between each source and a rail of the stretch for supplying current of the same polarity to the rails of the stretch from both sources.

2. In combination, a stretch of railway track comprising a plurality of successive track sections, a pair of line wires extending throughout said stretch, a track transformer for each section having its secondary connected with the rails of the section and its primary connected with said line wires, a source of train controlling current for each section for at times supplying current to the rails of the corresponding section, and means for preventing the flow of train controlling current in said line wires and including rectifiers one interposed between each said track transformer and a rail and another interposed between each said source and a rail.

3. In combination with a stretch of railway track, two transformers having their secondaries connected in parallel across the rails of said stretch, means for supplying alternating currents to the primaries of said transformers, and means for preventing current from either transformer from flowing through the other transformer and including two rectifiers one connected between each secondary and a rail of the stretch, and two other rectifiers one connected across each secondary and the rectifier associated therewith.

4. In combination, a stretch of railway track, two transformers having their secondaries connected in parallel across the rails of said stretch, means for supplying alternating currents of different frequencies to the primaries of said transformers, two rectifiers one interposed between each transformer and a rail in such manner that said transformers supply current to the rails during corresponding half cycles of such cur-

rent, and two other rectifiers one connected in parallel with each secondary and the associated rectifier and offering its higher resistance to current from the associated transformer during such half cycles.

5. In combination with a stretch of railway track comprising a plurality of successive track sections, two sources of alternating current for each section connected in parallel with the rails of such section, and means comprising a rectifier interposed between each source and a rail of the associated section for preventing current from any source from flowing through the other source 15 for the same section.

6. In combination, a stretch of railway track comprising a plurality of successive track sections, a first and a second pair of line wires extending throughout the stretch, 20 a track transformer for each section having its primary connected with the first pair of line wires, a track relay for each section responsive to current in the associated track rails, a train control transformer for each section having its primary connected with the second pair of line wires over a front contact of the track relay for an adjacent section, the secondaries of the track transformer and the train control transformer for 25 each section being connected in parallel across the rails of the corresponding section and a rectifier interposed between each secondary and a rail of the corresponding section for preventing current from any 30 train control transformer from flowing

through the secondary of the associated track transformer.

7. In combination, a stretch of railway track, two sources of alternating current of different frequencies connected with the rails 40 of said stretch, and two rectifiers one interposed between each source and a rail of the stretch for suppressing half cycles of the same relative polarity in the current from both sources.

8. In combination, a pair of conductors, two sources of alternating current of different frequencies connected with said conductors, and two rectifiers one interposed between each said source and one of said 50 conductors for supplying current of the same polarity to the conductors from both sources.

9. In combination, a pair of conductors, two transformers having their secondaries 55 connected in parallel across said conductors, means for supplying alternating currents of different frequencies to the primaries of said transformers, two rectifiers one interposed between each transformer and a conductor 60 in such manner that the transformers supply current to the conductors during corresponding half cycles of such current and two other rectifiers one connected in parallel with each secondary and the associated rectifier and offering its higher resistance to current from the associated transformer during such half cycles.

In testimony whereof I affix my signature.
HOWARD A. THOMPSON.
